UNITED STATES PATENT OFFICE.

ARCHIBALD MALLINSON, OF MONTREAL, QUEBEC, CANADA.

FEED MECHANISM IN A VEGETABLE PACKAGING MACHINE.

Application filed May 22, 1925. Serial No. 32,233.

The invention relates to a feed mechanism in a vegetable packaging machine, as described in the present specification and illustrated in the accompanying drawings that 5 form part of the same.

The invention consists essentially of the novel features of construction pointed out broadly and specifically in the claims for novelty following a description containing 10 an explanation in detail of an acceptable form of the invention.

The objects of the invention are to take the potatoes direct from a bin or freight car, boat, scow or other means of transport or 15 storage and parcel them in packages, of even sizes and weights ready for delivery to the dealer, or to the consumer; to avoid clogging up the passages by means of which the potatoes reach the bag for packaging purposes; to eliminate damage to the potatoes or such other vegetable or fruit as may be 20 fed into the machines; to reduce the labor required for the continuous performance of the machine to the minimum; to facilitate 25 the marketing of the potatoes at a reasonable cost to the public; and to provide an accurate and efficient machine, durable, serviceable and economical.

In the drawings, Figure 1 is a side elevation 30 of the machine.

Figure 2 is a front elevation of the machine.

Figure 3 is a rear elevation of the machine.

Figure 4 is a longitudinal sectional view 35 through the feed box and hopper.

Figure 5 is a reduced view of the machine, showing its application and endless feed carrier attachment.

Figure 6 is a detail of a chute from the feed box showing a side view of the loose bottom.

Figure 7 is a detail showing a front view of the loose bottom illustrated in Figure 6.

Figure 8 is an enlarged detail of the operating shaft and foot levers for the measures.

Figure 9 is a reduced plan view of the carriage and machine frames omitting the feed box.

Figure 10 is a plan view of the feed box and hopper showing the distributors.

Figure 11 is a detail of a rotary spider forming the distributor showing it in plan 55 and cross section.

Figure 12 is a detail showing the measures in side elevation.

Figure 13 is a detail showing an end view of the measures.

Figure 14 is a detail of the fixed outlet 60 plate of the measures.

Figure 15 is a plan view of the operating shafts and gears for the feed box.

Like numerals of reference indicate corresponding parts in the various figures. 65

Referring to the drawings, the carriage 30 is formed of an open frame having the longitudinal bars 31, cross bars 32 and 33 secured to the bars 31, and the vertical bars 34 forming the bearings for the axles 35 of 70 the running gear having the wheels 36 and 37.

The machine frame 38 is riveted to the carriage frame intermediate of the length of the latter and carries at the upper end feed 75 box 39 having the hopper formed by the deflecting plates 40 and 41, said plates extending inwardly from the ends respectively and separated centrally at 42 and 43 to direct the potatoes centrally into the box. These plates 80 slope downwardly and inwardly as runways for the potatoes to the bottom 44 of the hopper, this bottom being shortened at the ends to form the outlet openings 45 and 46, extending in each instance for the full width 85 of the hopper.

The chute 47 leads from the outlet 45 and the chute 48 leads from the outlet 46, each chute having a loose bottom 49 agitated by a cam 50 beyond a sprocket 51 connected by a 90 chain 52 to a sprocket 53.

Each of the chutes 47 and 48 ends in a discharge chamber 54 of its own and each chamber has an outlet opening registering with the measures formed by the cylinders 95 55 and 56 and 57 and particularly with one cylinder at a time as they are rotated with the end disks 58, said disks being secured to the shaft 59 which is journaled in the rigid bearings 60 from the machine frame. 100

The bearings carry a disk 61 rigidly secured thereto and having the discharge opening 62 registering with the cylinders in turn and directing the potatoes into the funnels 63 and bags 64 encircling the necks of said 105 funnels which here correspond to a scale pan.

The bottom 44 of the feed box is swept by the rotary spiders 65 and 66, which maintain the potatoes in constant agitation and at the same time bring them into single file 110

on the convex side of the spiders where they cannot very well bunch and thereby sort them out into lines to tumble in file order over the edges of the outlet openings 45 and 46 and so on to the measuring cylinders and bags.

The rotary distributing spiders 65 and 66 are each formed of the convexed arms 67 radiating from the hub 68 in substantially 10 S-shape and tapering and turned rearwardly in respect to the direction of rotation. The hubs 68 are fixedly mounted on the shafts 69 and said shafts 69 are journalled in bearings in the bottom 44.

15 The worm gears 70 are mounted at the lower ends of the shafts 69 and coact with worms 71 on the shaft 72, which is journalled in the bearings 73 supported by the machine frame (see Figures 1, 4 and 15). The shaft 20 72 is driven by the worm 74 mounted on the shaft 75 and operating the worm wheel 76 on said shaft 72, said shaft 75 being driven by the motor 77 through the chain and sprocket drive 78 from the motor shaft, said 25 motor being carried on the shelf 79 of a bracket extending from a side wall of the feed box. The shaft 72 also carries the sprocket 51 mentioned in the foregoing and the chain 52 as stated connects said sprocket 30 51 with the sprocket 53, mounted on a driving shaft for the endless carrier as herein-after more particularly explained.

35 The rotary spiders maintain the incoming potatoes in constant movement and bring them over to the feed box outlets in three lines of potatoes, one potato after another to be dropped over the edge quickly and continuously. Therefore the feed is not interrupted while there are potatoes in the 40 hopper.

45 The fixed disks 61 each have an auxiliary outlet 80 closed by a swinging cover 81, this outlet forming an additional opening for taking one or more potatoes usually found in the cylinders not discharging and used in adding to short weight bags by hand following the weighing operation.

The angle brackets 82 from the funnels 63 form the supports for the bags, which 50 encircle the necks of the funnels to form the packages.

55 The suspension rods 83 extend upwardly from the funnels and hang said funnels and angle brackets from the scale mechanisms 84 and the scale arms 85, these mechanisms being operatively connected to the indicators 86 and of any conventional construction.

60 The shafts 59 at their upper ends extend through to the bearings 87 from the feed box and at their lower ends downwardly to and through the bearings 88 from the carriage frame.

65 The operating arms 89 or other form of levers are mounted on the shafts 59 at the lower ends and carry the stop collars 90 en-

gaged by the springs 91 to maintain the inlet and discharge hole of the cylinders 55, 56 and 57 in proper register intermittently.

The measuring cylinders and weighing mechanism are on either side of the machine frame 38 beyond which the feed box 39 extends to support said cylinders and discharge thereinto.

In the operation of this invention the machine is customarily used in unloading potatoes directly from a freight car or boat, so in that way the packages are made ready for the customer without handling the potatoes many times.

75 The potatoes are first loaded on a conveyer 80 of conventional design, which extends into the bin and leads to the hopper and feed box. A suitable connection 165 is made from the motor of the machine to the conveyer shaft 166 and the potatoes thus carried without interruption to the hopper where, they roll down the inclined runways to the central portion of the bottom of the feed box. The rotary distributing spiders then gently 85 engage the incoming potatoes and spread them around, until they are carried in rotation by the spider arms and strung in line and finally dropped over the edges of the bottom at the feed box outlets.

95 The potatoes roll down the chutes from the feed box outlets and as the bottoms of said chutes are constantly moving, there is no tendency on the part of the potatoes to collect and obstruct the passage to the discharge outlets.

100 The outlets from the chutes are of good size and the measures turn around in the area of this outlet, so that one measure is filled to the brim, while another receives some potatoes at the same time to prevent choking at the mouth of the measure operating mechanism.

105 The full measure turns to the outlet opening in the fixed plate and another measure takes its place for filling.

110 The measure reaching the outlet, the potatoes empty quickly therefrom and roll into the bag through the funnel and are then weighed and if found under weight, the auxiliary opening in the fixed plate may be 115 uncovered and a potato or two taken from the partially filled measure, or if overweight a potato may be taken away, and placed on a table, bench or shelf. The bag is then removed and replaced by an empty bag, and the foot lever of the measure shaft kicked to bring around the next full measure to the outlet opening.

120 What I claim is:—

125 1. In a vegetable packaging machine, a hopper and rotary spiders having shafts journalled in a plate below said hopper and radial arms with rounded upper surfaces and having their ends turned rearwardly with respect to the direction of rotation and 130

in cooperative relationship sweeping the incoming vegetables successively in respect to their blades or sweeps into discharge openings and chutes from said openings.

5 2. In a feed mechanism in a vegetable packaging machine, a hopper and feed box therebelow and rotary spiders sweeping the bottom of said box in the direction of opening at each end extending for the full width 10 of the box, and chutes from said openings.

3. In a feed mechanism in a vegetable packaging machine, a hopper forming at the lower end a distributing feed box having a bottom shortened at the ends to leave discharge openings, a pair of sweeping members 15 suitably rotated and chutes from said openings.

4. In a feed mechanism in a vegetable packaging machine, a hopper and distributing 20 feed box combined formed with side and end walls, inner inclined runways to a central feed opening and a shortened bottom leaving discharge openings, means agitating and distributing the vegetables and chutes 25 from said openings.

5. In a feed mechanism in a vegetable packaging machine, a hopper and distribut-

ing feed box combined having guide plates between the side walls and secured thereto leading in a downwardly inclined direction 30 to a central feed opening extending across the box and terminating above the box bottom, rotary spiders having arms sweeping said bottom and journaled under said guide plates and suitably rotated thereunder, and 35 chutes leading from said box.

6. In a feed mechanism in a vegetable packaging machine, a hopper feed box having shaft bearings in the bottom thereof and discharge openings at the ends of said bottom, shafts journaled in said bearings 40 and worm wheels mounted at the lower end thereof, rotary spiders mounted on the upper ends of said shafts and sweeping said bottom, a worm shaft journaled in suitable bearings and having worms operatively engaging said worm wheels, a worm wheel mounted on said worm shaft and a worm shaft suitably journaled and having 45 a worm driving the worm wheel on said worm shaft.

Signed at Montreal, Canada, this 24th day of April, 1925.

ARCHIBALD MALLINSON.
